UNITED STATES PATENT OFFICE.

HENRY WILLIAM ST. DENIS AND WALTER ST. DENNIS, OF OTTAWA, ONTARIO, CANADA.

DESIGN FOR A ROCKING OR HOBBY ELEPHANT.

43,948.

Specification for Design.

Patented Apr. 29, 1913.

Application filed February 3, 1913. Serial No. 746,066. Term of patent 7 years.

To all whom it may concern:

Be it known that we, HENRY WILLIAM ST. DENIS and WALTER ST. DENNIS, subjects of the King of Great Britain, residing in the city of Ottawa, Province of Ontario, Dominion of Canada, have invented a new, original, and ornamental Design for a Rocking or Hobby Elephant, of which the following is the specification, reference being had to the accompanying drawing, forming part thereof.

The figure is a perspective view of a rocking elephant, showing our new design.

We claim—

The ornamental design for a rocking or hobby elephant, as shown.

Ottawa, Jan. 30/13.

HENRY WILLIAM ST. DENIS.
WALTER ST. DENNIS.
